UNITED STATES PATENT OFFICE

WALTER M. HANNEMAN, OF EVANSVILLE, INDIANA, ASSIGNOR TO UNION SPECIAL MACHINE COMPANY, OF CHICAGO, ILLINOIS, A CORPORATION OF ILLINOIS

THREAD CONTROLLING MECHANISM FOR SEWING MACHINES

Application filed September 8, 1928. Serial No. 304,633.

The invention relates to new and useful improvements in thread controlling mechanisms for sewing machines and more particularly to a rotating thread controller.

5 An object of the invention is to provide a thread controlling mechanism which includes a rotating thread controlling element having laterally projecting thread controlling cams with which is associated a stationary thread 10 cam wherein said thread controlling cams are so constructed as to maintain the thread under positive control during the entire rotation of the thread controlling member.

A further object of the invention is to provide a thread controlling mechanism of the 15 above type having an inner thread guide and an outer thread guide which are stationary and positioned so as to maintain the thread in engagement with the rotating thread 20 controlling element and wherein the inner thread guide is so constructed that it may be readily threaded.

A further object of the invention is to provide a thread controlling mechanism of the 25 above type wherein the inner and outer thread guides are independently adjustable.

A still further object of the invention is to provide a thread controlling mechanism of the above type wherein the stationary thread 30 cam is mounted for circumferential adjustment relative to the rotating thread cam.

These and other objects will in part be obvious and will in part be hereinafter more fully disclosed.

35 In the drawings which show by way of illustration one embodiment of the invention:—

Fig. 1 is a plan view of the parts of a portion of a sewing machine embodying the improvements.

Fig. 2 is a view showing more or less diagrammatically the position of the thread controlling element and the parts immediately 45 associated therewith when the looper is at the forward end of its stroke.

Fig. 3 is a view showing diagrammatically the position of the needle and looper when the controller is in the position illustrated 50 in Fig. 2.

Fig. 4 is a sectional view on the line 4—4 of Fig. 2.

Fig. 5 is a view similar to Fig. 2, but showing the looper and needle positioned so that the needle point is well into the looper thread 55 triangle.

Fig. 6 is a view showing the position of the needle and looper when the controller is in the position shown in Fig. 5.

Fig. 7 is a sectional view on the line 7—7 of Fig. 5.

Fig. 8 is a view of the thread controller when the looper is at the rear end of its stroke.

Fig. 9 is a plan view of the thread controller at the time when the looper is just entering 65 the needle thread loop.

Fig. 10 is a sectional view on the line 10—10 of Fig. 1.

Fig. 11 is a plan view of the inner thread guide, the stationary thread cam, and the 70 means for supporting the same.

Fig. 12 is a sectional view on the line 12—12 of Fig. 1 showing the manner of mounting the outer thread guide.

Fig. 13 is a development of the rotary 75 thread controlling cam.

The invention is directed to a thread controller for sewing machines and more particularly to a thread controlling mechanism for the looper thread of a sewing machine. 80

This thread controlling mechanism includes a rotary thread controlling cam provided with a supporting disc and a laterally projecting cylindrical thread controlling cam member. Associated with this rotary thread 85

controlling element is an inner thread guide and an outer thread guide. The rotary thread controlling element is provided with two similar cylindrical projecting members, the free edges of which are shaped to form 90

take-up cams and these projecting members are spaced from each other. There is a stationary thread cam which lies between the cylindrical projecting members. This stationary thread cam and the inner thread 95

guide are both mounted on a collar which is capable of being shifted so as to adjust the thread guide and take-up cam in a direction circumferentially of the rotary thread controlling element. The outer thread guide is 100

hinged so that it may be swung to a convenient position for threading. The rotary thread controlling element is so positioned relative to the thread guides and the stationary thread controlling cam that the looper thread is given up to the looper after the looper point has entered the needle thread loop, and while the looper is moving forward to the end of its stroke. When the looper starts to retract the thread controlling cam takes up the looper thread and thus takes the slack out of the looper thread between the eye of the looper and the previous stitch. After the point of the needle is well into the thread triangle, then the thread controller gives up slack to the looper thread while the looper is moving to the rear end of its stroke. When the looper starts forwards the thread controller will again take up the looper thread and draw the thread back from the eye of the looper and thus prevent the looper thread from buckling in front of the eye of the looper and causing the looper to skip the needle thread loop.

Referring more in detail to the drawings, the machine as shown includes a supporting bed 1 on which the parts of the machine are mounted. Mounted in suitable supporting brackets carried by the bed is the main actuating shaft 2. The looper is indicated at 3 in the drawings, and the needle at 4. The means for operating the needle and the looper may be of any desired construction. The looper, as shown, is mounted on a rocker 5 and the rocker 5 is oscillated through a suitable cam on the main shaft for giving to the looper its needle avoiding movement.

There is a rock shaft mounted on the bed of the machine which is oscillated by an eccentric on the main shaft and this rock shaft through a link 7 imparts oscillations to the looper. The present invention is directed to the thread controlling mechanism and this thread controlling mechanism includes a rotary thread controlling element 8 which is provided with a hub 9 by which the controlling element is secured to the main actuating shaft. This rotary thread controlling element also includes a supporting disc 10 carrying laterally projecting cylinders 11 and 12 which are radially spaced from each other. The free edges of these cylinders are curved and shaped so as to provide the active thread engaging surfaces of the controlling element. The looper thread passes from the supply through suitable guides beneath the nipper spring 13 of the usual character. It then passes to an inner thread guide 14. This inner thread guide 14 has a guiding eye 15 and an inclined face 16 leading to the guide 15. This inner guide 15 is open so that the thread when moved along the inclined surface 16 will drop into said thread guide. The thread passes from this inner thread guide 14 to the outer thread guide 17 which is carried

at the outer end of an arm 18. The arm 18 is fixed to a pivot rod 19 mounted in a suitable bracket 20. A spring 21 serves to hold this thread guide either in its normal position for the operation of the machine or in a raised position to which it may be moved to make it readily accessible for threading. The thread passes from this outer thread guide to the looper.

Associated with the rotary thread controlling element is a stationary thread cam 22. This stationary thread cam 22 is provided with an inclined face 23. The stationary thread cam and also the inner thread guide are mounted on a collar, which collar is clamped to a stationary sleeve 24 surrounding the main actuating shaft.

When the parts are in the position shown in Fig. 2 the needle is at the upper end of its stroke and the looper is at the forward end of its stroke. At this time the thread passes substantially in a straight line from the inner thread guide 15 to the outer thread guide 17. Slack has been given to the looper for the purpose of permitting it to freely move to the extreme end of its forward stroke without unduly straining and breaking the thread.

At this time the portion of the thread controlling element indicated at *a* is directly opposite the looper thread (see Fig. 13). As the looper retracts the thread controlling surface between the point *a* and the point *b* comes into contact with the looper thread and will carry said thread into contact with the stationary thread cam, and the thread will be forced along the inclined face 23 and thus move farther away from the thread guides. During this time the looper is on its retracting stroke and the looper thread is taken up and drawn taut so that the looper thread running from the eye of the looper to the previous stitch is taut when the point of the needle moves into the looper thread triangle. As the looper continues its backward movement the portion of the controlling cam between the point *b* and the point *c* comes into contact with the thread and will gradually give up thread to the looper, permitting the looper to freely move to the rear end of its stroke. As the looper starts on its forward movement the portion of the thread controlling cam between the point *c* and the point *d* comes into contact with the looper thread and will again take up the looper thread drawing the same back through the point of the looper and thus preventing the looper thread from buckling in front of the eye of the looper and causing a skipping of stitches. Just as soon as the looper point is well into the needle thread loop then the portion of the thread controlling cam between the point *d* and the point *a* comes into contact with the looper thread and gradually gives up looper thread to the looper as it moves to the forward end of its stroke, as has already been described.

The only time that the looper thread is entirely released from the stationary cam is when the looper is reaching the forward end of its stroke and a considerable amount of thread is desired to permit the proper movement of the looper. At all other times the looper thread is under positive control and is either gradually being taken up by the rotating thread controlling element or gradually given up by the rotating thread controlling element. This maintains the looper thread under constant control during the movements of the looper. If the looper thread should break there is no chance for it to be wound on to the rotating shaft as the stationary sleeve surrounding the shaft and carrying the inner thread guide and stationary thread cam is directly beneath the controlling cam edge of the rotary thread controller. The arm 18 carrying the outer thread guide 17 is secured to the supporting bracket therefor by means of screws 20a, 20a passing through slots 20b in the arm 18 and threaded into the bracket 20. Thus it is that the outer thread guide may be adjusted circumferentially of the shaft 2 and relative to the inner thread guide. The inner thread guide 14 is carried by an arm 14a which is curved to conform to the sleeve 24 and is secured thereto by a screw 14b passing through a slot (not shown) and this enables the inner thread guide 14 to be adjusted in a circumferential direction about the shaft 2 and relative to the outer thread guide. The stationary cam 22 is carried by a split collar 22a which is clamped to the sleeve by means of a bolt 22b, and thus it is that the stationary cam 22 may be shifted to various set positions.

It will be noted that the looper thread is not only under constant control during the entire rotation of the thread controlling element, being given up gradually as required for use by the looper, but the thread is at no time strained or jerked as often occurs where cast-offs are necessary for casting the thread off from moving cams.

It is obvious that minor changes in the details of construction and the arrangement of the parts may be made without departing from the spirit of the invention as set forth in the appended claims.

Having fully described my invention, what I claim as new and desire to secure by Letters Patent, is:

1. A thread controller for sewing machines comprising a rotating shaft, a thread controlling element mounted on said shaft and having a laterally projecting cylindrical flange, thread guides located within and without the periphery of the flange, a stationary cam cooperating with said rotating controller, the edge of said flange being shaped so that the thread is under constant control during the taking up and giving up of the thread and said stationary cam being so positioned rela-

tive to the rotating controller as to cooperate therewith in the taking up of the thread and the giving up of the thread.

2. A thread controller for sewing machines comprising a rotating shaft, a thread controlling element mounted on said shaft and having a laterally projecting cylindrical flange, thread guides located within and without the periphery of the flange, a stationary cam cooperating with said rotating controller, the edge of said flange being shaped so as to provide a continuous curved edge gradually extending outwardly and thence inwardly and again outwardly and inwardly so that the thread is under constant control and is taken up and given up twice for each rotation of the controlling element and said stationary cam being so positioned relative to the rotating controller as to cooperate therewith in the taking up of the thread and the giving up of the thread.

3. A thread controller for the looper thread of a sewing machine comprising a rotating shaft, a thread controlling element mounted on said shaft and having a laterally projecting cylindrical flange, thread guides located within and without the periphery of the flange for holding the thread in contact with the flange, a stationary cam cooperating with said rotating element, the edge of said flange being shaped and the stationary cam disposed so that the looper thread is taken up as the looper moves forward to enter the needle thread loop and is then given up to the looper gradually under control as the looper moves to the end of its stroke.

4. A thread controller for the looper thread of a sewing machine comprising a rotating shaft, a thread controlling element mounted on said shaft and having a laterally projecting cylindrical flange, thread guides located within and without the periphery of the flange for holding the thread in contact with the flange, a stationary cam cooperating with said rotating element, the edge of said flange being shaped and the stationary cam disposed so that the looper thread is gradually taken up as the looper begins its retracting movement and is gradually given up under control after the point of the needle enters the looper thread triangle and until said looper reaches the end of its retracting stroke.

5. A thread controller for sewing machines comprising a rotating shaft, a thread controlling element mounted on said shaft and having a laterally projecting cylindrical flange, thread guides located within and without the periphery of the flange, a stationary cam cooperating with said rotating controller, the edge of said flange being shaped so that the thread is under constant control during the taking up and giving up of the thread, said inner thread guide being mounted so that it may be adjusted in a circumferential direction around said shaft.

6. A thread controller for sewing machines comprising a rotating shaft, a thread controlling element mounted on said shaft and having a laterally projecting cylindrical flange, thread guides located within and without the periphery of the flange, a stationary cam cooperating with said rotating controller, the edge of said flange being shaped so that the thread is under constant control during the taking up and giving up of the thread, said stationary cam being mounted so that it may be adjusted in a circumferential direction around said shaft. 70
- 10 7. A thread controller for sewing machines comprising a rotating shaft, a thread controlling element mounted on said shaft and having a laterally projecting cylindrical flange, thread guides located within and without the periphery of the flange, a stationary cam cooperating with said rotating controller, the edge of said flange being shaped so that the thread is under constant control during the taking up and giving up of the thread, said inner thread guide and 80 said stationary cam being mounted on a collar clamped to a stationary sleeve surrounding said shaft and adjustable so that the thread guide and cam may be shifted in a circumferential direction about the axis of the 85 shaft. 90
- 15 8. A thread controller for sewing machines comprising a rotating shaft, a thread controlling element mounted on said shaft and having a laterally projecting cylindrical flange, thread guides located within and without the periphery of the flange, a stationary cam cooperating with said rotating controller, the edge of said flange being shaped so that the thread is under constant control 100 during the taking up and giving up of the thread, said outer thread guide being mounted so that it is capable of adjustment toward and from a vertical plane containing the axis of the shaft. 105
- 20 9. A thread controller for sewing machines comprising a rotating shaft, a thread controlling element mounted on said shaft and having a laterally projecting cylindrical flange, thread guides located within and without the periphery of the flange, a stationary cam cooperating with said rotating controller, the edge of said flange being shaped so that the thread is under constant control 110 during the taking up and giving up of the thread, said outer thread guide being mounted so that it is capable of adjustment toward and from a vertical plane containing the axis of the shaft, and means for supporting said outer thread guide whereby it may be raised to a position readily accessible for threading. 115
- 25 10. A thread controller for sewing machines comprising a rotating shaft, a thread controlling element mounted on said shaft and having radially spaced laterally project- 120
- 30 ing cylindrical flanges, thread guides located within and without the periphery of said flanges for holding the thread in contact therewith, a stationary cam disposed between said cylindrical flanges having an inclined face for engagement with the thread, said flanges being curved continuously outwardly and inwardly and said stationary cam being disposed so as to maintain positive control 125 on the thread during the entire rotation of the controlling element. 130
- 35 11. A thread controller for sewing machines comprising a rotating shaft, a thread controlling element mounted on said shaft and having radially spaced laterally project- 135
- 40 ing cylindrical flanges, thread guides located within and without the periphery of said flanges for holding the thread in contact therewith, a stationary cam disposed between said cylindrical flanges having an inclined face for engagement with the thread, said flanges being curved continuously outwardly and inwardly so as to maintain positive control 140 on the thread during the entire rotation of the controlling element, and means for supporting said stationary thread cam whereby it may be adjusted in a circumferential direction about the axis of the shaft. 145
- 45 12. A thread controller for sewing machines comprising a rotating shaft, a thread controlling element mounted on said shaft and having radially spaced laterally project- 150
- 50 ing cylindrical flanges, thread guides located within and without the periphery of said flanges for holding the thread in contact therewith, a stationary cam disposed between said cylindrical flanges having an inclined face for engagement with the thread, said flanges being curved continuously outwardly and inwardly so as to maintain positive control 155 on the thread during the entire rotation of the controlling element, said inner thread guide and said stationary cam being mounted on a collar clamped to a stationary sleeve surrounding the shaft and adjustable circumferentially about the axis of the shaft. 160
- 55 13. A thread controller for sewing machines comprising a rotating shaft, a thread controlling element mounted on said shaft and having radially spaced laterally project- 165
- 60 ing cylindrical flanges, thread guides located within and without the periphery of said flanges for holding the thread in contact therewith, a stationary cam disposed between said cylindrical flanges having an inclined face for engagement with the thread, said flanges being curved continuously outwardly and inwardly and said stationary cam being disposed so as to maintain positive control 170 on the thread during the entire rotation of the controlling element, said thread guides being disposed so that the thread is substantially straight between the guides at the maximum inward point in the 175

curved face of the thread controlling element.

14. A thread controller for sewing machines comprising a rotating shaft, a thread controlling element mounted on said shaft and having radially spaced laterally projecting cylindrical flanges, thread guides located within and without the periphery of said flanges for holding the thread in contact therewith, a stationary cam disposed between said cylindrical flanges having an inclined face for engagement with the thread, said flanges being curved continuously outwardly and inwardly so as to maintain positive control on the thread during the entire rotation of the controlling element, said thread guides being disposed so that the thread is substantially straight between the guides at the maximum inward point in the curved face of the thread controlling element, and means whereby said inner and outer guides may be independently adjusted toward or from a vertical plane containing the axis of the shaft.

25 15. In a thread controlling mechanism for sewing machines, the combination of a rotating shaft, an annular member mounted on and rotating with said shaft and having a thread engaging face, a stationary member having a cam-shaped thread engaging face operating when in engagement with the thread to force the thread into contact with the thread engaging face on said rotating annular member, said thread engaging faces on the annular member and on the stationary member being shaped and positioned so as to gradually take up the thread and gradually give up the thread held in contact with said faces.

40 In testimony whereof, I affix my signature.
WALTER M. HANNEMAN.
